UNITED STATES PATENT OFFICE

WALTER MYERS, OF BRIDGEPORT, CONNECTICUT, ASSIGNOR TO THE SINGER MANUFACTURING COMPANY, OF ELIZABETH, NEW JERSEY, A CORPORATION OF NEW JERSEY

STOP-MOTION DEVICE FOR SEWING MACHINES

Original application filed January 26, 1928, Serial No. 249,506. Divided and this application filed September 29, 1928. Serial No. 309,143.

This invention relates to improvements in sewing machines for embroidering and more especially to embroidering machines of the type having a universal work-feeding mechanism directionally controllable manually during the operation of the machine, the present application being a division of my prior patent application filed January 26, 1928, with Serial No. 249,506.

10 The primary object of this invention is to adapt universal-feed embroidering machines for conveniently sewing and embroidering any portion of work of large sizes, such as carpets or rugs, the present improvement being directed to the controlling means for determining the action and inaction of the stitch-forming and work-feeding mechanisms.

20 In a commercial embodiment of the present invention, the machine is constructed with a cloth-plate and over-hanging bracket-arm sufficiently long to conveniently accommodate the work. To manually control the 25 operation of the stitch-forming and work-feeding mechanisms, a hand-crank is provided upon a short, vertical shaft journaled in the machine bracket-arm adjacent its head, which hand-crank controlled shaft is directly 30 geared to the feed-direction controlling shaft journaled in said bracket-arm, whereby the direction of feed may be conveniently controlled manually.

35 Through special connections housed within the bracket-arm of the machine, the hand-crank may be operated to determine the position of a coupling device shiftable to connect and disconnect the pulley-and needle-and-feed-actuating shafts commonly employed in machines of this type. The stopping position of the needle-and-feed-actuating shaft is 40 predetermined by the engagement with a stop-notch, formed on a member carrier by said shaft, of a spring-pressed plunger slidably supported for endwise movement in a bracket secured to the rear side of the machine bracket-arm.

45 In the accompanying drawings, Fig. 1 is a front side view in elevation and partly in section of a machine containing the present 50 improvements, the bracket-arm cover-plate

being removed. Fig. 2 is a front end elevation of the machine bracket-arm head and bed-plate, the feeding-foot being partly broken away. Fig. 3 is a detail view of the device employed for yieldingly holding the 55 needle-actuating shaft of the machine in inoperative position. Fig. 4 comprises perspective views of the feed-finger actuating cam and its support.

50 Referring to the drawings, the sewing machine is constructed with a cloth or bed-plate 1, from which rises the vertical standard 2 of the overhanging bracket-arm 3, terminating in the head 4 to which is suitably secured the supporting frame 5.

55 Journaled in a suitable bearing provided in the standard 2 is a short actuating shaft 6 carrying at its outer end the combined balance-wheel and belt-pulley 7. The shaft 6 is counter-bored at its inner end to provide a bearing for the reduced end 8 of the needle-and-feed-actuating shaft 9, the opposite end of the shaft 9 being journaled in a suitable bearing in the bracket-arm 3.

60 Supported for rotation about a vertical axis, in bearings provided in the supporting frame 5, is a cylinder 10 within the upper end of which is splined a short, hollow needle-bar 11 partaking of any rotations of the cylinder and capable of vertical reciprocations with respect to said cylinder. Secured within the needle-bar by a set-screw 65 12 is a hook-needle 13, the needle-bar 11 being operatively connected with a driver 14, vertically reciprocated in the usual manner from 70 the shaft 9.

75 Cooperating with the needle 13 below the cloth-plate, in the formation of either chain- or drop-stitches, is a vertical-axis looper 15 upon the upper end of a shaft 15' suitably journaled upon the machine-frame and having a spiral-gear 16 in mesh with a spiral driving-gear 17 upon the forward end of a rotary and endwise-reciprocatory shaft 18.

80 The looper-actuating shaft 18 is journaled for rotary and endwise reciprocatory movements in bearings provided in brackets 19, 20, depending from the cloth-plate 1, the shaft 18 adjacent its rearward end being 85 splined to the hub 21 of a bevel-gear 22 jour-

naled for rotation in a bearing-aperture in the bracket 20. At its rearward end, the shaft 18 is suitably connected with a depending arm 23 of a bell-crank lever fulcrumed 5 within the bracket-arm standard 2 upon a pivot-pin 24 disposed transversely of the length of the shaft 18. The other arm 25 of the bell-crank lever is suitably connected with the lower end of a pitman 26 provided 10 at its upper end with a strap 27 embracing an eccentric 28 having a hub 29 fixed upon the shaft 9. It will therefore be evident that when the shaft 9 is rotated, the shaft 18 derives endwise reciprocatory movements to 15 oscillate the looper 15 about its vertical axis to position the thread for engagement by the hooked needle in the usual manner.

The hub 29 of the eccentric 28 is embraced by the correspondingly recessed flange 30 of a 20 cam-sleeve 31, provided with a cam-groove 32 and slidingly mounted upon the shaft 9. Projecting from the flange 30 is a coupling-pin 33, slidable endwise through an aperture provided in the eccentric 28 and adapted to 25 enter an aperture in a coupling-collar 34 fixed upon the shaft 6. Bearing against the cam-sleeve 31 is a coil-spring 35, surrounding the shaft 9 and interposed between said cam-sleeve and a collar 36 fixed upon the shaft 9. 30 When permitted, the spring 35 acts to cause coupling engagement of the pin 33 with the collar 34, whereby the shaft 9 is joined to the shaft 6 for rotation therewith.

Means are provided for normally holding 35 the coupling-pin 33 disengaged from the collar 34, for which purpose the cam-groove 32 is entered by a roller carried by the free end of a vibratory-arm 37, pivotally supported upon the machine frame within the 40 standard 2. Adjustably connected to the arm 37, by means of an eccentric stud 38, is one end of a connecting-lever 39, disposed within the bracket-arm 3 and formed intermediate its ends with an elongated slot 40 to 45 provide guide-walls slidable upon a fulcrum-block 41, pivotally secured by means of a screw 42 to the machine frame. The other end of the lever 39 is shouldered to provide a depending latch-hook 43 adapted to be engaged by an upwardly directed latch-hook 44 formed on one end of a lever 45, pivotally supported within the bracket-arm 3 upon a pivot-screw 46. The latch-hook end of the lever 45 is yieldingly 50 urged upwardly to engage the latch-hook 43 by means of a spring 47 interposed between said lever and the bottom of the bracket-arm.

In Fig. 1 of the drawings, the lever 45 is shown as latched to the lever 39 whereby the 55 vibratory arm 37 is held against movement to the right. The arm 37 being held against movement to the right, it will be evident that upon further rotation of the shaft 9, the cam-sleeve 31 will be shifted to the left upon the 60 shaft 9, against the action of the spring 35,

which has the effect of withdrawing the coupling-pin 33 from the aperture in the collar 34. The shaft 9 thus disconnected from its driving power would eventually come to rest.

However, means are provided for predetermined the stopping position of the shaft 9. By referring to Fig. 3 of the drawings, it will be observed that the periphery of the cam-sleeve flange 30 is formed with a V-shaped stop-notch 48, which in the position occupied by the sleeve when uncoupled from its driver, is adapted to be entered by the wedge-shaped end of a plunger-head 49. The plunger-head 49 is slidingly supported for 75 endwise movement within the bore of a tubular bracket 50 suitably secured in an aperture in the rear side of the standard 2, said plunger-head having a reduced extension 51, surrounded by a coil-spring 52 interposed between the plunger-head and an adjustable bushing 53 threaded into the bracket 50. The inward movement of the plunger under the action of the spring 52 is adjustably limited by a nut 54 threaded upon the outer end 80 of the plunger-extension 51 and engaging the head of the bushing 53. The adjustment provided by the eccentric stud 38 affords means for slightly altering the timing to insure entrance of the flange-notch 48 by the 85 plunger 49.

In order to rotate the cylinder 10 under manual control, there is secured upon said cylinder a bevel-gear 55 in mesh with a similar gear 56 upon the forward end of a feed-direction controlling shaft 57 journaled for rotation in bearings provided in the bracket-arm 3. Intermediate its ends, there is secured upon the shaft 57 a bevel-gear 58 meshing with a like gear 59 secured upon the upper end of a tubular shaft 60 projecting within the bracket-arm 3. The tubular shaft 60 is journaled for rotation about a vertical axis in a bearing provided by a boss 61 depending from the bracket-arm 3. Secured upon the end of the shaft 60 projecting below the boss 61 is a crank-arm 62 carrying a crank-handle 63, which as usual in machines of this type is capable of slight movement in a direction at right angles and with respect to the crank-arm 62. The crank-handle 63 has a peripheral groove 64 operatively engaging one arm of a lever 65 fulcrumed intermediate its ends upon the crank-arm 62. Engaged by the flattened end 66 of the lever 65 is a pin 67 slidingly disposed within the tubular shaft 60, the upper end of the pin 67 being positioned to engage the depending end 68 of the lever 45. It is apparent that a downward movement of the crank-handle 63, effected manually, causes a rocking movement of the lever 45, against the action of the spring 47, to release the connecting lever 39 and thereby permit the spring 35 to effect in due course the coupling of the shafts 6 and 9. 130

Heretofore in machines of this type, when the nature of the work was such as to permit of continuous stitching, certain of the parts of the stop-motion controlling mechanism 5 were removed from the machine so as to obviate the requirement for the operator to maintain the shafts 6 and 9 coupled by constant depression of the crank-handle 63. To in a simple manner provide for continuous 10 stitching, a screw 69 is threaded into the hub of the crank-arm 62 in a position such that it may be caused to engage and secure the pin 67. Therefore, when the pin 67 is elevated to disconnect the stop-motion controlling 15 levers 39, 45, it may readily be secured in its raised position by means of the screw 69.

The rearward end of the feed-direction controlling shaft 57 is geared to the upper end of a vertical shaft 70, journaled for rotation in bearings provided in the standard 20 2 and carrying at its lower end a bevel-gear 71 meshing with the bevel-gear 22, which as before described is splined to the looper-actuating shaft 18. It will therefore be 25 understood that by rotating the crank-handle 63, the cylinder 10 and the needle-carrying bar 11 splined thereto will be likewise rotated, as well as the looper to properly present the thread to the needle.

30 The feeding mechanism of this machine, with the exception of the feed-length adjusting mechanism, is substantially as disclosed in greater detail in my prior Patent No. 1,325,033, December 16, 1919. This feeding mechanism includes a feeding-foot or ring 72 which is detachably secured upon the lower end of a feed-bar 73 supported at its upper end for universal movement about transverse pivotal axes in a manner to permit 35 the feed direction to change upon rotation of the cylinder 10 by the crank-handle 63.

In the present instance, the extent of work-feeding movement of the feeding-foot is determined by adjustment of the vertically reciprocating cam-member 74 about an axis approximately coincident with the point of engagement of the usual feed-lever 75 with said cam member. To this end, the cam-member is provided with spaced arms 76 40 having upon their inner surfaces the curved guide-ribs 77 (only one of which is shown) slidably disposed in correspondingly curved guideways 78 (only one of which is shown) provided in the opposite flat sides of a fulcrum-block 79. The cam-member arms 76 are provided with arcuate slots 80 through which extends a pin 81, secured in a transverse aperture 82 in the fulcrum-block by 45 means of a set-screw 83. Threaded upon the opposite ends of the pin 81 are nuts 84, whereby the cam-member is secured upon the fulcrum-block in adjusted position. The fulcrum-block has a grooved collar 85 embraced 50 by the forked arm 86 of the usual vertically

reciprocating sleeve 87, whereby feeding movements are imparted to the feed-bar.

Having thus set forth the nature of the invention, what I claim herein is:—

1. In a universal-feed sewing machine, a cloth-plate, a bracket comprising a vertically directed standard from which extends laterally a bracket-arm overhanging the cloth-plate, a main shaft, a needle- and feed-actuating shaft, coupling means for connecting and disconnecting said shafts, and means for controlling the action of said coupling means during the operation of said main shaft including a manually operable member carried by the overhanging arm of the bracket, and connections with said member extending lengthwise of the overhanging arm of the bracket. 70

2. In a universal-feed sewing machine, a cloth-plate, a bracket-arm overhanging the cloth-plate, a main-shaft, a needle- and feed-actuating shaft, and a stop-motion device for determining the operation of said needle- and feed-actuating shaft, said stop-motion device including connectible levers disposed 85 successively lengthwise of the overhanging portion of said bracket-arm, and a manually operable member for controlling the connection of said levers to thereby control the operation of said stop-motion device. 90

3. In a universal-feed sewing machine, a cloth-plate, a bracket-arm overhanging the cloth-plate, a main-shaft, a needle- and feed-actuating shaft, coupling means for said shafts including a shiftable cam-sleeve, a vibratory-arm actuated by said cam-sleeve, a connecting-lever extending lengthwise of the overhanging portion of said bracket-arm operatively connected with said vibratory-arm, a latch-lever normally acting to hold said connecting-lever in position to effect uncoupling of said shafts, and a manually operable member disposed above said cloth-plate for at will rendering said latch-lever ineffective. 100

4. In a universal-feed sewing machine, a cloth-plate, a bracket-arm overhanging the cloth-plate, a reciprocating needle, a feeding-foot, a main-shaft, a needle- and feed-actuating shaft, coupling means for said shafts including a shiftable cam-sleeve, a vibratory-arm actuated by said cam-sleeve, a connecting lever housed within said bracket-arm operatively connected with said vibratory-arm, a latch-device acting to hold said lever in position to effect uncoupling of said shafts, 110 and a manually actuated hand-crank journaled in said bracket-arm operable to determine the direction of feed of the work and to render said latch-device ineffective. 115

5. In a universal-feed sewing machine, a reciprocating needle, a feeding-foot, a main-shaft, a needle- and feed-actuating shaft, coupling-means for said shafts including a shiftable cam-sleeve provided with a coupling-pin and a stop-notch, a vibratory-arm actuated 125 130

by said cam-sleeve, means for manually controlling the vibration of said arm to thereby control the operation of said needle- and feed- actuating shaft, a plunger adapted to engage said cam-sleeve stop-notch to determine the stopping position of the needle, a spring urging said plunger into engagement with said cam-sleeve, means for adjusting the pressure of said spring, and adjustable means for limiting the movement of the plunger under the action of said spring.

In testimony whereof, I have signed my name to this specification.

WALTER MYERS.
